(57) **CLAIM**

The ornamental design for a sequencing instrument, as shown and described.

DESCRIPTION

FIG. 1 is a front, right top perspective view of a first embodiment of a sequencing instrument illustrating our new design;

FIG. 2 is a front, right bottom perspective view of the design of FIG. 1;

FIG. 3 is a front, left top perspective view of the design of FIG. 1;

FIG. 4 is a front, left bottom perspective view of the design of FIG. 1;

FIG. 5 is a rear, left top perspective view of the design of FIG. 1;

FIG. 6 is a rear, left bottom perspective view of the design of FIG. 1;

FIG. 7 is a rear, right top perspective view of the design of FIG. 1;

FIG. 8 is a rear, right bottom perspective view of the design of FIG. 1;

FIG. 9 is a front elevational view of the design of FIG. 1;

FIG. 10 is a right side elevational view of the design of FIG. 1;

FIG. 11 is a left side elevational view of the design of FIG. 1;

FIG. 12 is a rear elevational view of the design of FIG. 1;

FIG. 13 is a top plan view of the design of FIG. 1;

FIG. 14 is a bottom plan view of the design of FIG. 1;

FIG. 15 is an enlarged partial, front, right bottom perspective view of the design of FIG. 1;

FIG. 16 is an enlarged partial, front, left bottom perspective view of the design of FIG. 1;

FIG. 17 is an enlarged partial, front, right top perspective view of the design of FIG. 1;

(Continued)

FIG. 18 is an enlarged partial, front, right top perspective view of the design of FIG. 1;
 FIG. 19 is an enlarged partial, front, left top perspective view of the design of FIG. 1;
 FIG. 20 is an enlarged partial, front, left top perspective view of the design of FIG. 1;
 FIG. 21 is an enlarged partial, front, top perspective view of the design of FIG. 1;
 FIG. 22 is an enlarged partial, front, top perspective view of the design of FIG. 1;
 FIG. 23 is an enlarged partial, rear, right top perspective view of the design of FIG. 1;
 FIG. 24 is an enlarged partial, rear, left top perspective view of the design of FIG. 1;
 FIG. 25 is an enlarged partial, top plan view of the design of FIG. 1;
 FIG. 26 is a front, right top perspective view of a second embodiment of a sequencing instrument illustrating our new design;
 FIG. 27 is a front, left top perspective view of the design of FIG. 26;
 FIG. 28 is an enlarged partial, front, right top perspective view of the design of FIG. 26;
 FIG. 29 is an enlarged partial, front, right top perspective view of the design of FIG. 26;
 FIG. 30 is an enlarged partial, front, left top perspective view of the design of FIG. 26;
 FIG. 31 is an enlarged partial, front, left top perspective view of the design of FIG. 26;
 FIG. 32 is an enlarged partial, front, top perspective view of the design of FIG. 26;
 FIG. 33 is an enlarged partial, front, top perspective view of the design of FIG. 26;
 FIG. 34 is an enlarged partial, rear, right top perspective view of the design of FIG. 26;
 FIG. 35 is an enlarged partial, rear, left top perspective view of the design of FIG. 26; and,
 FIG. 36 is an enlarged partial, top plan view of the design of FIG. 26.
 The dashed lines, the areas within them, and the unshaded areas bounded by both broken lines and solid lines depict portions of the sequencing instrument that form no part of the claimed design. The long dash-short dash lines depict the bounds of the claimed design and form no part thereof.
 The dot-dot-dash lines shown in FIGS. 15, 16, 18, 20, 21, 22-25, 29, 31, 32, and 33-36 represent the bounds of the enlarged views and form no part of the claimed design. The dot-dot-dot-dash lines shown in FIGS. 17, 19, 21, 28, 30, and 32 represent symbolic breaks. The symbolic break lines and the areas outside of the symbolic breaks form no part of the claimed design.

1 Claim, 36 Drawing Sheets
